Primary Examiner—Gary D. Watson(74) *Attorney, Agent, or Firm*—Maginot, Moore & Beck**(57) CLAIM**

The ornamental design for a chair seat, as shown and described.

DESCRIPTION

FIG. 1 is a perspective view of a chair seat showing our new design.

FIG. 2 is a front view of our chair seat shown with arms in broken lines for illustrated purposes only.

FIG. 3 is a perspective view of our chair seat mounted on an alternative frame.

FIG. 4 is a front elevational view of the chair seat shown in FIG. 3.

FIG. 5 is a side elevational view of the chair seat shown in FIG. 3; and,

FIG. 6 is a rear elevational view of the chair seat shown in FIG. 3.

Broken lines are also used to define boundaries.
